No. 36,850.

Patented March 15, 1904.

UNITED STATES PATENT OFFICE.

WILLIAM M. RHOADS, OF DENVER, COLORADO.

DESIGN FOR A BOOK-COVER.

SPECIFICATION forming part of Design No. 36,850, dated March 15, 1904.

Application filed February 6, 1904. Serial No. 192,456. Term of patent 14 years.

To all whom it may concern:

Be it known that I, WILLIAM M. RHOADS, a citizen of the United States of America, residing at the city and county of Denver, State of Colorado, have invented a new, original, and ornamental Design for Book-Covers, of which the following is a specification, reference being had to the accompanying drawing, which forms a part of this specification.

10 The figure is an elevation of the outside of both covers of a book-cover.

What I claim as new, and desire to secure by Letters Patent, is—

The ornamental design for a book-cover, substantially as shown.

WILLIAM M. RHOADS.
